HEATING PROCESS AND APPARATUS

Albert L. Klees, New York, N. Y., assignor to
 Combustion Utilities Corporation, New York,
 N. Y., a corporation of Maine

Application April 8, 1933, Serial No. 665,053

20 Claims. (Cl. 263—15)

The present invention relates to industrial high temperature heating and heat-treating operations, and more especially it relates to a process and apparatus for the heating of materials in a manner generally following the principles of diffusion combustion, but in which process pulverized solid fuels are utilized instead of the usual combustible fluids.

The principles of diffusion combustion are now well known. In accordance therewith, contacting parallel streams of air and gaseous or vaporized fuels are flowed into and through a furnace under conditions of velocity and temperature such that controlled progressive combustion of the fuel constituents occurs throughout the path of flow within the furnace, while turbulence is substantially reduced to a minimum. Applications of diffusion type combustion employing fluid fuel are now in successful commercial use; and these involve many improvements over prior known methods,—including an increased rate of heat transfer to the material being heated with a substantially lower flame temperature. Furthermore, undue refractory wear is minimized thus greatly reducing routine repairs; and the heating process is stabilized, insuring consistent quality of product and uniform results.

The usual powdered solid fuel is not normally adapted for use in a process involving diffusion combustion. Heretofore the use of powdered coal in industrial furnace operation has usually involved the employment of a mixing burner design necessitating a high velocity of flow both of the powdered fuel and of the combustion air entering the combustion chamber. One reason for the necessity for high flow velocities in prior processes has been that the usual type of solid fuel pulverizers employed in the past has produced a considerable amount of fuel particles of a size substantially larger than 100 mesh; and high velocities are required to convey these large particles to and into the combustion zone. The said high velocities were further needed in order to give an intensity of combustion which would promote the complete burning of these larger size fuel particles. Intensity and rapidity of combustion have always been desirable, in order to complete the combustion of the fuel within the smallest possible combustion space.

The fact that these very high flow velocities have been required in the past for the combustion of powdered coal has heretofore strongly militated against its use in a combustion opera-

tion based in whole or in part upon the diffusion principle,—such as that set out fully in patent application Serial No. 424,280 of Stephen P. Burke, filed Jan. 29, 1930; and in my copending patent application Serial No. 620,576 filed July 2, 1932.

Among the more important objects of the present invention therefore are: To provide for a heating or combustion operation employing solid fuel or mixtures containing the same, in accordance with the diffusion flame principle of combustion; and to provide in novel manner for the preparation and regulated combustion of a fuel mixture of uniform selected heating value and containing powdered solid fuel.

The present invention is based in substantial part upon the discovery that if a solid fuel is pulverized to a point where about 80 per cent or more thereof will pass through a 200 mesh sieve, and 99 per cent plus will pass through a 100 mesh sieve,—and if the thus-pulverized solid fuel is diluted with and suspended in sufficient hot inert gases or flue gases to produce a combustible mixture having a heating value of from 200 to 3000 B. t. u. per cu. ft. and is then introduced into a combustion chamber or furnace in a series of spaced parallel streams or sheets, interspersed with flowing streams of a combustion-supporting gas such as air,—the combustion of the solid fuel in the streams of flue gases occurs progressively as the latter flow through the furnace toward the furnace outlet.

Because of the fine division of the pulverized solid fuel, the minute particles of fuel and of ash therefrom are in major part carried along in suspension in the stream of combustion gases, the ash being discharged through the stack, so that substantially no contamination of the materials being heated occurs. In many types of heating operations, the presence of small amounts of ash upon the material being heated is immaterial, as is the case in the production of steel in an open-hearth furnace such as hereinabove described.

Referring now to the accompanying drawings illustrating certain features of the present invention:

Fig. 1 is a side elevation, partly in section, of a billet heating furnace;

Fig. 2 is a transverse section taken along the line 2—2 of Fig. 1, looking in the direction of the arrows;

Fig. 3 is a perspective view of one form of burner assembly, parts being broken away;

Fig. 4 is a vertical section through another

form of burner assembly, taken along the line 4-4 of Fig. 5, looking in the direction of the arrows;

Fig. 5 is an end elevation of the burner assembly of Fig. 4;

Fig. 6 is a somewhat diagrammatic view, partly in section, showing an open-hearth furnace and associated parts; and Fig. 7 is a corresponding view, partly in section, of another form of open-hearth furnace and associated parts.

Referring to the drawings, numeral 10 designates a furnace suitably lined with a refractory material. An elongated heating and combustion chamber 12 of approximately uniform cross-section throughout its length has a work-receiving end wall 14, provided with an opening controlled by a door 16.

The opposite end of the chamber 12 has a throat 18, the floor of which preferably is disposed above the floor 20 of the chamber 12 a distance approximately equal to the height of the work to be heated therein. A work charging device 22 is provided at the end 14 of the furnace for introducing into the chamber 12 materials to be heated. Work-supporting tracks 24 are provided, which may be hollow and water-cooled. An inclined work-discharge chute 26 having therein a pair of spaced closing members 28, 30, is adapted to permit removal of the work while preventing substantial fluid flow between the furnace and the outer atmosphere.

For removing the products of combustion from the chamber 12, a flue 32 is provided in one or both side walls of the furnace adjacent the work-receiving end,—the same communicating through passageway 34 with a horizontal flue or recuperator heating chamber 36 disposed below the chamber 12,—the opposite end of the chamber 36 being connected with a stack 38 controlled by stack valve 40.

Referring now to the form of burner construction more particularly set out in Figs. 1 and 3, there is provided a burner tube assembly 45 comprising an elongated hollow rectangular casing 42 of heat resistant material such as high melting point oxidation resistant metal or alloy, preferably lined or coated with non-metallic refractory material, such as that disclosed in the copending application, Serial No. 417,391 of John D. Morgan, filed December 30, 1929. The interior of the casing is divided into a plurality of spaced, parallel superposed fuel passageways or ducts 44, interspersed with a plurality of air passageways or ducts 46,—by means of respective pairs of partition members 48, 50, disposed adjacent each other and having their side margins provide a gas-tight fit with the side walls of the casing 42. A tapered fuel mixture distributing member 52 is secured to one end of the casing 42 for distributing fuel mixture to the respective fuel ducts. The members 48 and 50 are respectively flared or curved in a direction away from each other at their inlet ends 65 adjacent the distributing member 52, so that the curved forward margins of each member 48, 50, excepting the top-most and lower-most ones, engages the next adjacent member and is sealed thereto. By this construction the fuel mixture flowing through the member 52 is uniformly distributed within the respective fuel ducts 44. The forward part of each fuel duct 44 is provided with a constricted section tending to locally increase the rate of flow of the fuel suspension and correct for any undue lack of uni-

formity of the powdered coal-flue gas mixture flowing thereto from member 52. The portions of the members 48 and 50 at the outlet ends of the fuel ducts are substantially parallel thus serving to discharge the fuel mixture from the furnace in parallel spaced streams.

For introducing air or other combustion-supporting gas into the burner ducts 46, 46, and for distributing it therein in uniform manner, the casing 42 adjacent the fuel inlet end has its width increased as shown at 54 to form vertical air passageways 56 each connected with a conduit 58 leading to the outlet of an air pump or fan 60. Each passageway 56 is in permanent communication with each of the air ducts 46, 46 as shown; but the closed side walls of the respective fuel ducts 44, 44 prevent access of the air to the space within the same, as clearly indicated in the drawings. A series of screens 62 may, if desired, be positioned within the respective air ducts 46, 46 for further facilitating the uniform distribution of air around the respective fuel streams leaving the burner,—although such screens are not necessary to the practice of the invention.

The various parts of the burner are preferably made out of heat-resistant metal or alloys similar to that forming the casing 42. The surfaces forming the inner walls of the respective air ducts 46, 46 preferably are provided with refractory coating applied and secured thereto in any well known manner, such as that disclosed in the aforementioned copending patent application of John D. Morgan. The total cross-sectional area of the air ducts 46, 46 is of course much greater than that of the fuel ducts 44, 44, since a much larger volume of air than fuel mixture is required for the substantially complete combustion of the latter.

The lowermost slot or duct in the burner assembly is preferably a fuel duct 44 adapted to provide a flowing blanket of pulverized solid fuel in inert or reducing gases or flue gases,—which blanket flows over the work in the heating chamber in a direction generally parallel to the longitudinal axis of the furnace and forms a protective atmosphere between the work and the actively combusting fuel. The burner construction may be modified to adjust the thickness of this flowing blanket of floating solid fuel.

For grinding and pulverizing the solid fuels to be utilized, such as bituminous coal, anthracite coal, petroleum coke, ordinary coke, lignite, etc., to a suitable degree of fineness whereby it may be utilized properly in connection with the present invention, there is provided,—in the modification of the invention illustrated,—an impact mill of well known type in the nature of a ball mill 70, adapted to be rotated by a motor 72 through suitable gearing 74 at a speed which causes steel balls therein to be carried around by centrifugal force to a point where they are thrown down on the material within the mill, whereby there is a continuous cascade of these balls, delivering thousands of impacts per second, and serving to reduce the solid fuel to a fineness such that over 80 per cent, and generally around 85 to 95 per cent thereof, will pass through a 200-mesh sieve, and around 60 to 70 per cent thereof will pass through a 300-mesh sieve.

The solid fuel to be ground is fed from a hopper 76 to the inlet end of the ball mill 70 by a disc or other feeder 78 preferably driven

by a small variable speed motor (not shown). An enclosed fan 80 is connected with the discharge end of the mill 70 and is driven by a variable speed motor 81. The fan draws flue gases or other inert or reducing gases through the pulverizer 70 at a rate adapted to remove from the latter only the impalpable powder of the size herein indicated, which flows in suspension past the fan and is discharged to and through conduits 82 and 84 to the flared fuel-distributing member 52 mounted or formed in the refractory lining of the furnace 10.

For producing continuously a uniform mixture of the finely pulverized fuel and for suspending the latter in substantially inert flue gases in accordance with this form of the invention, the interior of the ball mill during operation is continuously swept by a stream of flue gases, preferably those withdrawn from the stack 38. For this purpose a lagged valve-controlled conduit 86 leads from the stack 38 directly to the inlet end of the ball mill 70. A valve-controlled bypass line 88 having therein a blower 90 directly connects the conduit 86 with the fuel-distributing member 52 of the burner assembly, bypassing the ball mill, and facilitates regulated dilution with inert gases of the fuel suspension flowing from the ball mill 70, when this is desired. A valve-controlled conduit 92, connected with the conduit 88, is adapted to supply combustible gas or a combustible mixture to the burner for heating up the furnace when starting up or to dilute the powdered fuel mixture flowing to the burner when desired.

For introducing hot air into the air-distributing passageways or headers 56 at a regulated rate and temperature, there is provided a fan 60 having its discharge outlet connected with conduit 58. The inlet end of the fan is connected through a valved recuperator conduit 94 with the outer atmosphere, the said conduit extending through the heating chamber 36 for the purpose of preheating the air. The inlet end of the fan 60 is also connected with a valved cold air conduit 96 for introducing cold air into the burner housing, or for tempering the pre-heated air entering the fan through conduit 94. The fan 60 preferably is driven by a constant speed motor, (not shown); and regulation of the air flow is by the valves in the air conduits 94 and 96.

For bringing the cold furnace up to the desired operating temperature and for initially producing flue gases having sufficient heat and the desired composition for the practice of the process, a combustible gas or gas mixture may be introduced into the furnace through the burner from line 92,—air being supplied to the furnace at the same time by means of the blower 60, or through the air conduit 98 leading to a burner 100. Fuel gas, or oil, or both, may be introduced for the same purpose into the combustion chamber through one or more valved conduits 102 and combusted with air introduced to the burner through the said conduit 98 or in other suitable manner.

As soon as the furnace has reached the desired operating temperature and hot flue gases are being generated, the flow of oil or gas and air through the conduits 92, 98 and 102 preferably is discontinued;—although a lean natural gas or an artificial gas such as coke-oven gas, cracking still gas, or water gas, may, if desired, be introduced through conduit 92 during op-

eration, for continuously and uniformly adjusting the heating value of the fuel suspension flowing from the pulverizer 70.

In the form of the burner construction shown in Figs. 4 and 5, there is provided a casing 110 adapted to house a plurality of elongated tubular members 112, the said casing having its forward or inlet end secured to the distributing member 52. The forward or inlet end of each fuel tube 112 adjacent the member 52 has an enlarged or flared mouth portion 114; and each tube is provided with a constriction forming a Venturi orifice 116 immediately rearwardly of the flared inlet. The mid-portion of the tubular members and all portions rearwardly thereof have substantially parallel walls as shown in Fig. 4. Surrounding each tubular member 112 is a larger concentric tubular member 118, each opening into the furnace at its outlet end, and at its other end being in permanent communication with a flue-gas header 120 which is fed by flue gas flowing through valve-controlled conduit 122 connected with a suitable source of flue gas under pressure, such as conduit 86. This forms a plurality of annular flue gas passageways or ducts 123 surrounding each tubular member 112. An annular air passageway 124 is provided which extends around each of the flue gas ducts 123 and is fed with air from the air conduit 58.

In the modification of the invention illustrated in Fig. 6, an open-hearth furnace 150 having the usual hearth 151 is provided with the checkerwork regenerators 152, 152', respectively connected with opposite ends of a melting and refining chamber 154 through suitable waste gas flues 156, 156' controlled by dampers 158, 158'. The lower parts of the respective regenerators 152, 152' are connected with a stack conduit 160 by means of the respective branch conduits 162, 162' and damper 164,—the arrangement being such that when flue gases are flowing to the stack from one of the regenerators, the gas outlet from the other regenerator is closed.

For introducing air for combustion into the regenerators, there is provided air conduit 166 through which air under suitable pressure flows from an external source. The conduit 166 is adapted to be selectively connected with either of the regenerators 152, 152' through the respective conduits 168, 168' and the damper 170. Mounted in the upper part of the furnace at opposite ends of the hearth or combustion and melting zone 151 is a pair of opposed burner assemblies of the diffusion type, such as heretofore described. The casing 42 of each burner has its outlet end located somewhat distant from the respective waste gas flues 156, 156' to prevent or limit actual contact therewith of the hot combustion gases flowing through these flues at certain stages in the operation of the furnace. The respective fuel distributing members 52 are selectively connected through conduits 172, 172' and valve 174 with the pulverizer 70.

For introducing a regulated amount of flue gases at suitable velocity and temperature into the pulverizer, and for providing a fuel mixture of regulated heating value,—a conduit 176 having therein a blower or pump 178 connects stack conduit 160 with a valved branch conduit 180 communicating with the inlet end of the pulverizer and with a valved conduit 182 leading directly to the inlet of fan 80.

For conducting air at a regulated rate to the air header 56 of each burner assembly there

are provided valve-controlled air conduits 184, 184', connecting each air header with a corresponding regenerator 152, 152', and adapted to function upon proper adjustment of the respective valves or dampers 158, 158'. According to this modification, a single pulverizer serves each of the opposed burners of a single open-hearth furnace.

The form of the invention illustrated in Fig. 7 10 is adapted for the operation of open-hearth furnaces, whereby a separate pulverizer successfully feeds fuel mixture to each burner of the furnace. This modification is in most respects similar to that illustrated in Fig. 6, with the following 15 exception: air for combustion is fed through the conduit 200, and is directed by damper 202 selectively to one of the regenerators 152, 152'. The damper 202 concurrently connects the other of the regenerators with a waste gas duct 204 20 leading to a stack (not shown). Preheated air is delivered to the respective air headers 56 of each burner assembly through valve-controlled air conduits 206, 206' having therein blowers 208, 208.

25 In the ordinary practice of the present invention, in connection with the form of apparatus shown in Fig. 1, a suitable solid fuel such as anthracite, semi-bituminous, or bituminous coal, metallurgical coke, petroleum coke, lignite char 30 and the like, is subjected to a high degree of pulverization in the pulverizer or mill 70; and the pulverized fuel is suspended in a current of inert or substantially inert gases to form a fuel suspension continuously having a uniform regulated heating value, preferably within the range 35 of from 200 to 3000 B. t. u. per cu. ft.

Assuming the furnace to be at a high operating 40 temperature, fuel to be pulverized is fed from the hopper 76 by the disc feeder 78 at a uniform regulated rate to the inlet of the mill where it is finely pulverized generally to a degree whereby 60 per cent thereof passes through a 300-mesh, over 80 per cent passes through 200-mesh, 99 plus per cent passes through 100-mesh 45 and 100 per cent passes through a 50-mesh screen. The higher the degree of diffusion flame combustion desired, the more finely should the material be pulverized; so that for a very high type of diffusion combustion operation the material should be pulverized to a point where 99 plus per cent passes through a 200-mesh sieve; and in some cases even to a point where 99 plus 50 per cent of the pulverized material passes through a 325-mesh screen.

55 During pulverization of the solid fuel, a stream of hot flue gases withdrawn from the stack 38 or from other suitable source of supply is passed through the pulverizer 70 and serves as a hot carrier fluid for the material drawn from the pulverizer under the action of fan 80 for discharge to the burner assembly. These hot flue gases may be replaced if desired, by any other hot inert or relatively inactive gas such as nitrogen, or water vapor and the like. In some instances a small amount of air may be added to the flue gases. The temperature of the flue gases passing to the pulverizer 70 preferably is within the range of 650° to 800° F. Temperatures substantially higher than this are not recommended. Any hydrocarbon gases or vapors released from the solid fuel during its pulverization and suspension in the hot carrier gases flow with the suspension of fuel in flue gases to the burner assembly. For the regulated dilution of 70 the pulverized fuel suspension when desired,

prior to the passage thereof into the burner assembly in order to control the velocity of flow of the pulverized fuel mixture through the burner assembly to the furnace independently of the amount and size of the pulverized fuel particles being produced in the pulverizer, a regulated portion of the hot flue gases may be forced by fan 90 through the valve-controlled conduit 88 directly into the fuel suspension flowing in conduit 82. In this manner a fuel suspension of 10 uniform B. t. u. value is caused to flow continuously through the distributing header 52 into and through the burner ducts. The Venturi-shaped constriction in the forward portion of each of the fuel ducts in the burner is adapted 15 still further to increase the velocity of the fuel mixture within the fuel ducts to maintain the intimacy of the intermixture and to prevent the deposit of solid fuel within these tubes.

Where 350-mesh pulverized fuel is employed, 20 the conditions preferably are so selected that the fuel suspension flows within the burner ducts at a velocity of around 10 to 15 ft. per second; while if fuel is employed of a size such that 90 per cent will pass through a 200-mesh sieve and 25 99 plus per cent passes through a 100-mesh sieve, a somewhat higher velocity of around 25 ft. per second through the burner tubes is more desirable.

When once the solid fuel enters the highly 30 heated combustion chamber of the furnace, the rate of flow of the fuel may be safely increased in the practice of the invention; and in long combustion or work-heating chambers, flow velocities of from 25 to 100 ft. per second are 35 desirable, depending upon whether the fineness of pulverization is such as to yield a fuel 99 plus per cent of which passes through a 325-mesh sieve,—or is such that 90 percent will pass through a 200-mesh sieve and 99 per cent plus 40 passes through a 300-mesh sieve.

Concurrently with the flow of fuel, preheated air under suitable pressure to control its velocity of flow to the furnace enters the burner casing through the conduits 53 and is uniformly distributed within the air ducts 46. The arrangement is such that a fuel duct is interposed between adjacent air ducts. The parallel streams of suspended solid fuel and of air contact with each other as they enter the furnace throat, 50 and are ignited due to the high temperature therein. The velocity of flow of the fuel suspension and the air streams is preferably so regulated that these streams flow at approximately the same velocity as they enter the furnace. Gradual mixing of the streams of fuel and air thereafter occurs largely by interdiffusion as the combustion progressively proceeds at the surfaces of contact of the contiguous fuel and air streams and at the surfaces of the individual 60 fuel particles adjacent such surfaces of contact.

The heat of the hot carrier gases serves to release combustible volatiles from the pulverized solid fuel when such is present therein,—and 65 these volatiles flow to the burner with the fuel suspension. Due to the limited temperature of the fuel suspension and the nature of the components thereof, no objectionable reactions occur between these components prior to their introduction into the furnace combustion zone.

The total transverse cross-sectional area of the fuel ducts and of the air ducts preferably is so selected as to facilitate maintenance of the respective streams at approximate equal veloci- 75

ties as they enter the furnace and in suitable proportions for substantially complete combustion of the fuel. While a somewhat overventilated flame is desired for many operations,—it is within the scope of the invention to use either a neutral flame or an underventilated flame.

Due to the high temperature of the flue gases, and to a furnace construction free from abrupt changes in transverse cross section, turbulence of the flowing gases is still further inhibited,—thus greatly retarding the rate of intermixture of gases, while permitting the formation in the furnace of carbon particles within the fuel streams from the cracking of any hydrocarbons released from the solid fuel during or subsequent to pulverization of the fuel. The incandescent carbon persists in the gases flowing through the furnace so as to effectively radiate heat to the furnace and work over a large portion of its path of travel therein.

After the furnace has been brought to the temperature required for the heating operation, such as a temperature in the range from 2200° to 2900° F., the work is moved into the furnace and is exposed to the highly heated combustion gases containing therein incandescent carbon, thus rapidly heating the work,—the gases thereafter passing to the flue 38 through the recuperator.

When employing a pulverized fuel suspension containing fuel particles a major portion of which range in size from 200 to 325 mesh, it is preferred to employ burner port velocities ranging from 10 to 30 ft. per second. In order to prevent these velocities from producing an undesirable degree of turbulence within the furnace such as would serve to interfere with the desired control of the rapidity and intensity of the combustion therein,—this tendency is offset by suitable adjustment of the B. t. u. value of the fuel suspension. Having selected the burner port velocities required to prevent undesirable degree of turbulence,—a combustion control to regulate the flame temperature is effected by reducing the concentration of fuel particles in the fuel suspension moving to the furnace. This may be accomplished by limiting the amount of hot gases drawn through the pulverizer, and by maintaining the desired velocity of hot flue gases by diluting the fuel suspension with hot gases flowing through the conduit 38. Furthermore, by lowering the B. t. u. content of the fuel suspension, it is possible to satisfactorily utilize lower port velocities, since lowering the concentration of fuel particles in the flue gas lowers the velocities necessary to move the said particles to the furnace. Generally it is desired to employ the minimum fuel and air velocities through the burner ports which will result in a maximum of diffusion flame combustion.

Having selected the desired velocities to be employed to obtain the desired diffusion flame combustion, the B. t. u. concentration of the solid fuel suspension in the flue gases is now adjusted; in general the lower the B. t. u. concentration at a given velocity, the slower the combustion, and the higher the B. t. u. concentration the more rapid the combustion with resultant higher flame temperatures. Where the quantity of flue gases available is unlimited, the intensity of the flame may be varied as desired by thus adjusting the concentration of the solid fuel in the flue gases,—more particularly where a high degree of diffusion flame combustion is

desirable. In other instances where such high degree of diffusion combustion is not essential, and where the quantity of flue gases is limited, the rate and intensity of combustion may be increased by correspondingly increasing the fuel and air velocities at the burner ports.

In certain instances it may not be practicable to secure control of the rate and intensity of combustion within desired limits either by varying the burner port velocities or by adjusting the B. t. u. content of the pulverized fuel suspension. Under such conditions a further control of combustion is secured by the utilization of the type of burner assembly illustrated in Figs. 4 and 5,—in the use of which a surrounding layer or sheet of flue gases or other inert or relatively inactive fluid is interposed between each stream of pulverized fuel suspension and the surrounding air stream as they leave the burner. These protective streams or layers of inert gases serve to keep the reacting components of the fuel and air streams separated for a substantial length of time after entry into the combustion chamber, and provides a reasonable degree of control of the rapidity of combustion.

This type of operation is of especial value in instances where it is absolutely necessary to use high velocity streams of the pulverized fuel suspension, or where extremely high concentrations of pulverized fuel suspension in flue gases are employed. Otherwise in such cases the degree of turbulence obtained might seriously interfere with the obtaining of a satisfactory degree of diffusion flame combustion. By means, however, of this blanket of flue gases between each fuel stream and contiguous air stream, the control of the rate at which the solid fuel particles contact with the air within the furnace facilitates combustion control even in instances where a considerable degree of turbulence occurs.

Such operation is especially desirable where insufficient pulverization of the solid fuel has occurred with the result that the particles require high velocity streams of flue gases for conveying them to the furnace. Somewhat greater control of the intensity and rapidity of combustion of the fuel particularly at high velocities is possible by this form of operation.

Where a high degree of diffusion flame combustion is necessary, it may occur at times that the amount of fuel required in the fuel suspension for providing a fuel mixture of desired B. t. u. value cannot readily be handled at the flue gas velocities available through the pulverizer. This can be compensated for at least in part by providing that the temperature of the flue gases used be as high as possible within the temperature range up to 900° F.

It has been determined that within reasonable limits the higher the temperature of the pulverized fuel suspension in the flue gases, the larger the amount of solid fuel particles which can be satisfactorily carried by the gas stream at a given velocity. The reason for this phenomenon is not entirely understood, but experimental work seems to indicate that when finely divided coal particles are heated they adsorb gas films at their surfaces, which greatly adds to their buoyancy and facilitates the preparation and maintenance of a suspension of such particles at velocities within the range set out here.

The above-mentioned adjustment for controlling the heating value of the fuel suspension flowing to the burner assembly is made by regulating the respective portions of hot flue gases

flowing through the pulverizer 70 and that flowing directly to the burner assembly through bypass line 88 under action of the fan 90.

The total volume of flue gases to be used for heating and suspending the pulverized fuel at the pulverizer 70 is largely determined by the amount of solid fuel and the particle size thereof required to be conveyed to the furnace per unit of time and by the temperature of these carrier gases. For instance, to provide a fuel suspension having a heating value of 600 B. t. u. per cu. ft. only approximately half the amount of flue gases is required that would be needed for the production of a 300 B. t. u. per cu. ft. fuel mixture.

Of course, the total amount of flue gases put through the pulverizer must be at least the minimum amount required to carry the desired amount of pulverized coal therefrom to the furnace burner assembly,—and this in turn depends upon the fineness of pulverization.

In the utilization of the invention in connection with a regenerative type of heating operation, such as carried out in an open-hearth furnace, the operation is in general the same as that previously described. A regulated flow of hot air to the respective burners is made possible by use of the blowers 208, 208. Moreover, a blower is provided for regulating the flow of flue gases to the pulverizer and burner assembly at each end of the furnace. In open-hearth furnace operation, the combustion air is preferably heated to around 1800° F. within the respective regenerators. It is particularly desirable therefore that the interior surface of the metal air ducts within each burner assembly be refractory lined. By suitable regulation of the dampers or valves in the lagged conduits 180, 182, respectively conducting hot flue gases to the pulverizer and directly to the burner assembly, the amount flowing to the former may be adjusted to give gas velocities within the pulverizer required for the proper suspension of the fuel. The remainder of the flue gases needed to adjust the heating value is added to the pulverized fuel suspension as the latter flows from the pulverizer to the burners.

In instances where the air and fuel suspension velocities are low and the air is preheated to a high temperature, such as in the range of around 1800° F., it is advantageous to employ in the process solid fuels which have been treated previously as by coking operations or by air or flue gas treatment at lower temperatures to eliminate or substantially reduce the coking properties of the material, and to reduce the combustible volatile content thereof to a selected value.

The ratio of the total air duct to total gas duct transverse cross sectional area will of course vary depending upon the B. t. u. value of the solid fuel suspension used, the relative velocities of the air and fuel streams, and the ratio of air to fuel used. In an instance in which the said fuel suspension had a heating value of 250 B. t. u. per cu. ft. this ratio was approximately 2½ to 1,—the velocities of the combustible fuel and air being approximately the same. The burners and associated parts are usually so designed that under normal operation of the open-hearth furnace, a flame is produced having a general average temperature of about 2900° F. The high luminosity and radiating power characteristic of diffusion type combustion produces a flame temperature and a heat distribution providing a satisfactory rate of heating but which is low

enough so as not to have a deleterious effect upon the life of the lining of the furnace and adjacent parts.

The invention is susceptible of modification within the scope of the appended claims.

I claim:

1. The method of operating furnaces, which comprises pulverizing a solid fuel while so passing a hot and substantially inert gas therethrough as to suspend in said gas fuel particles of a desired fineness, continuously advancing the resultant suspension at an elevated temperature toward a highly heated combustion zone of said furnace, and continuously and concurrently conducting the said hot fuel suspension and a heated combustion-supporting gas into said highly heated combustion zone in parallel superposed streams at regulated approximately equal velocities adapted to maintain in substantial degree a parallel flow of the said contacting streams within the combustion zone.

2. The method of operating furnaces, which comprises pulverizing a solid fuel while so passing a hot and substantially inert gas therethrough as to suspend in said gas fuel particles of a desired fineness, continuously advancing the resultant suspension at an elevated temperature toward a highly heated combustion zone of said furnace, and continuously and concurrently conducting the said hot fuel suspension and a heated combustion-supporting gas into said highly heated combustion zone in parallel superposed streams at regulated, approximately equal velocities adapted to maintain in substantial degree the parallel flow of the said contacting streams within the combustion zone, the lowermost stream consisting of the said fuel suspension.

3. The method of operating furnaces, which comprises finely pulverizing solid fuel, suspending the pulverized fuel in a stream of hot gases low in uncombined oxygen to provide a solid fuel suspension having a regulated uniform heating value and having a temperature near but below that at which substantial thermal decomposition of hydrocarbon in the fuel suspension occurs, thereafter flowing the said hot fuel suspension and a combustion-supporting gas into a highly-heated combustion zone in parallel contacting streams at approximately equal velocities not substantially greater than 100 ft. per second.

4. The method of operating furnaces which comprises pulverizing solid fuel to a size such that the major portion thereof passes through a 300-mesh sieve, suspending the finely pulverized fuel in a stream of hot gases low in uncombined oxygen to provide a hot fuel suspension having a uniform regulated heating value and a temperature substantially below that at which interaction occurs between ingredients of the fuel, thereafter concurrently flowing the said fuel suspension while hot and a combustion-supporting gas into a combustion zone of the furnace in parallel contacting streams at respective velocities substantially below the turbulent velocity range, thereby effecting a regulated combustion of the fuel particles and the production of flue gases.

5. The process as defined in claim 4, in accordance with which flue gases produced in the process and low in uncombined oxygen flow through the pulverizing zone, thereby producing the said suspension of the pulverized fuel.

6. The process as defined in claim 4, in accordance with which the said combustion-sup-

porting gas before its introduction into the combustion zone is preheated by heat regenerated from the flue gases produced in the process, and the pulverized fuel is suspended in a stream 5 of the hot flue gases prior to the flow of the fuel suspension to the combustion zone.

7. The method of operating furnaces, which comprises pulverizing solid fuel to a degree such that over 80 per cent thereof passes through a 10 200-mesh screen, continuously suspending the said finely pulverized fuel in a hot stream of gases low in uncombined oxygen to provide a fuel suspension having a uniform regulated heating value and having a temperature near but below 15 the carbonization temperature, thereafter concurrently flowing the said solid fuel suspension while hot and a combustion-supporting gas into contact with material to be heated within a highly heated reaction zone in parallel contacting 20 streams at approximately equal velocities, and sweeping the exposed surface of the material being heated with a protective layer of the said pulverized fuel suspension, flowing at approximately 25 the same velocity as the respective streams of fuel and air, and in a direction parallel thereto.

8. The method of heating and melting materials in an open-hearth furnace, which comprises continuously suspending pulverized solid 30 fuel in a stream of hot flue gases low in uncombined oxygen to provide a fuel suspension having a uniform regulated heating value, the said solid fuel being pulverized to such degree that over 35 80 per cent thereof passes through a 200-mesh sieve and at least 60 per cent thereof passes a 300-mesh sieve, the said fuel suspension having a temperature near but below that at which substantial thermal decomposition of any hydrocarbon therein occurs, thereafter concurrently 40 flowing the said solid fuel suspension while hot and a combustion-supporting gas in parallel contacting sheets flowing at approximately like velocities into a highly-heated reaction zone containing a mass of material to be melted, each 45 of the said sheets extending approximately the entire width of the reaction zone, periodically reversing the direction of flow within the reaction zone of the said sheets of the fuel suspension and the combustion-supporting gas, regenerating heat from the resultant flue gases 50 formed in the last-named zone, and utilizing the hot flue gases for suspending pulverized fuel to be subsequently used in the process.

9. The process as defined in claim 8, including 55 the step of flowing between the exposed surface of the material being melted and the burning fuel a protective layer of finely pulverized solid fuel in suspension in a stream of hot gases low in uncombined oxygen.

60 10. In combination a furnace having an elongated heating chamber, a burner disposed at one end of the said chamber, the burner having a casing and a plurality of parallel, tubular, superposed members therein, each of said members having an inlet end flared to cooperate with like ends of adjacent tubes, the flared ends of adjacent tubes being joined to form a plurality of slots defining passage-ways to the inlet ends of the tubular members, the outlet ends 65 of the tubular members being open, air passage-ways formed between the tubular members which are open at their outlet ends, each of said tubular members with the exception of the lowermost having air passage-way on its upper and lower sides, means for introducing air to

the air passage-ways and means for introducing a controlled volume of fuel to the tubular members.

11. In combination a furnace having an elongated heating chamber, a burner disposed at an end of said chamber, the burner having a casing and a plurality of parallel tubular chambers therein, each chamber having an inlet end flared to cooperate with like ends of adjacent tubes to form a plurality of slots defining openings to the tubular members at their inlet ends, said tubular members being spaced apart and open at their outlet ends, a fuel distributing header arranged to distribute fuel to each of said slots, an exhaust gas outlet for said furnace, a conduit for conducting flue gases from said exhaust gas outlet having controlling means for introducing predetermined volumes of flue gas to said distributing header, fuel pulverizing mechanism operatively connected with said distributing head and connected with said flue gas conduit so arranged as to be swept by a stream of flue gas from said conduit and valve-controlled means connecting the respective spaces between the tubular members with a source of 20 air supply.

12. In combination, a furnace having an elongated heating chamber, a burner assembly at an end of the said chamber, the said burner assembly being formed of a casing, a plurality of 30 parallel tubular members therein, a fuel distributing header connected with the inlet ends of the tubular members, the said inlet end of each tubular member being flared and secured to the corresponding ends of adjacent tubular 35 members, means for introducing air at a regulated rate within the casing and for distributing it uniformly around each of the said tubular members, a fuel-pulverizing mechanism having a fuel inlet, a gas inlet, and a fuel outlet, means for feeding solid fuel at a regulated rate to the said mechanism, a flue gas conduit connecting the furnace outlet with the fuel pulverizer gas-inlet, means connecting the outlet of the fuel pulverizer with the said burner, and 40 means for effecting a controlled flow of flue gases from the furnace through the pulverizer to the fuel-distributing member.

13. In combination a furnace having an elongated heating chamber of approximately uniform cross-section throughout its length, an exhaust gas outlet for said chamber, a burner disposed at one end of said chamber, said burner comprising a casing and a plurality of spaced tubular members therein, a fuel distributing 55 header surrounding the inlet end of the tubular members, the ends of adjacent members being secured together to form flaring inlet ends for the tubular members, said tubular members being spaced apart and open at their outlet ends to form air passages between the members, means operatively connected to the burner casing for introducing air into the air passage-ways, a fuel pulverizer, a conduit connected with the pulverizer and the exhaust gas outlet, 60 means for controlling the flow of flue gas to the pulverizer, a by-pass leading from said conduit to the distributing header, means for feeding solid fuel from the pulverizer to the distributing header at a regulated rate and means for 65 controlling the flow of flue gas from the conduit through the by-pass to the header.

14. In combination, a furnace having an elongated heating chamber, and a gas outlet, a burner disposed at one end of the said chamber,

- the burner having a casing containing a plurality of parallel tubular members each having an inlet end flared to cooperate with adjacent like ends to form an interconnected group of contiguous contacting ducts at the said inlet ends but which ducts are spaced apart at their outlet ends, a combustion air header, means connecting the latter with the spaces between the respective ducts, a fuel-distributing header connected with the said ducts, means operatively connected with the furnace gas outlet for conducting a regulated stream of furnace gases to the distributing header, fuel-pulverizing mechanism operatively connected with the last-named means and adapted to be swept by a stream of the furnace gases, and means for flowing flue gases at a regulated rate from the furnace through the fuel pulverizer.
15. In combination a furnace having an elongated chamber, a burner disposed at one end of the chamber and composed of a plurality of flat superposed tubular ducts, the adjacent ducts being spaced apart and opened at their outlet ends to form tubular passage-ways for air between the ducts, a valve-controlled conduct for supplying air to the passage-ways between the ducts, a fuel distributing header arranged to supply fuel to the inlet ends of each of said ducts, means for controlling the flow of fuel through the header, an exhaust gas recuperator chamber leading from said furnace, a recuperator conduit passing through the recuperator chamber and connected with said air supply conduit, a fuel pulverizing mechanism having an outlet connected with said header, means for feeding fuel at a regulated rate to the pulverizer and means for introducing gases into said pulverizer for carrying fuel from the pulverizer to the header.
20. An open-hearth furnace comprising in combination, a hearth, regenerative chambers respectively adjacent each of two opposite ends thereof, burner means respectively mounted in each of the said ends of the furnace at opposite sides of the hearth, the said burner means including a casing having therein a plurality of spaced parallel fuel ducts and being of approximately the same width as the hearth, means for the regulated introduction of air selectively to either casing between the said spaced fuel ducts therein, gas outlets disposed within the furnace respectively between the hearth and a corresponding burner, the said gas outlets being in regulated communication respectively with a corresponding regenerator, at least one gas-swept solid-fuel pulverizer adapted to be connected with each of the respective burners, means selectively connecting each of the regenerators with the pulverizer, and means for inducing a regulated flow of flue gases selectively from either regenerator through the pulverizer and to the corresponding burner.
25. An open-hearth furnace comprising in combination a hearth, burner assemblies respectively disposed at two opposite ends of the hearth, each of the said assemblies occupying at least a major portion of the width of the furnace at the said ends, each burner assembly having a plurality of parallel spaced fuel ducts interspersed with air ducts and arranged in close groups, a solid-fuel pulverizer in communication with the hearth through the fuel ducts, the air ducts being in regulated communication with a source of air, regenerators each in regulated communication with the furnace adjacent the hearth, valve-controlled means connecting each regenerator with the air ducts of a corresponding burner assembly, means in regulated communication with each regenerator and adapted to force combustion gases selectively from either regenerator through the pulverizer or directly to a burner assembly, and means for feeding a suspension of solid fuel in combustion gases from the pulverizer at a uniform regulated rate to the fuel ducts of a burner assembly.
30. An open-hearth furnace comprising in combination a hearth, burner assemblies respectively disposed at two opposite ends of the hearth, each of the said assemblies occupying at least a major portion of the width of the furnace at the said ends, each burner assembly having a plurality of parallel spaced fuel ducts interspersed with air ducts and arranged in close groups, a solid-fuel pulverizer in communication with the hearth through the fuel ducts, the air ducts being in regulated communication with a source of air, regenerators each in regulated communication with the furnace adjacent the hearth, valve-controlled means connecting each regenerator with the air ducts of a corresponding burner assembly, means in regulated communication with each regenerator and adapted to force combustion gases selectively from either regenerator through the pulverizer or directly to a burner assembly, and means for feeding a suspension of solid fuel in combustion gases from the pulverizer at a uniform regulated rate to the fuel ducts of a burner assembly.
35. An open-hearth furnace comprising in combination, a hearth, regenerative chambers respectively adjacent each of two opposite ends thereof, burner means respectively mounted in each of the said ends of the furnace at opposite sides of the hearth, the said burner means including a casing having therein a plurality of spaced parallel fuel ducts and being of approximately the same width as the hearth, means for the regulated introduction of air selectively to either casing between the said spaced fuel ducts therein, gas outlets disposed within the furnace respectively between the hearth and a corresponding burner, the said gas outlets being in regulated communication respectively with a corresponding regenerator, at least one gas-swept solid-fuel pulverizer adapted to be connected with each of the respective burners, means selectively connecting each of the regenerators with the pulverizer, and means for inducing a regulated flow of flue gases selectively from either regenerator through the pulverizer and to the corresponding burner.
40. An open-hearth furnace comprising in combination, a hearth, regenerative chambers respectively adjacent each of two opposite ends thereof, burner means respectively mounted in each of the said ends of the furnace at opposite sides of the hearth, the said burner means including a casing having therein a plurality of spaced parallel fuel ducts and being of approximately the same width as the hearth, means for the regulated introduction of air selectively to either casing between the said spaced fuel ducts therein, gas outlets disposed within the furnace respectively between the hearth and a corresponding burner, the said gas outlets being in regulated communication respectively with a corresponding regenerator, at least one gas-swept solid-fuel pulverizer adapted to be connected with each of the respective burners, means selectively connecting each of the regenerators with the pulverizer, and means for inducing a regulated flow of flue gases selectively from either regenerator through the pulverizer and to the corresponding burner.
45. An open-hearth furnace comprising in combination, a hearth, regenerative chambers respectively adjacent each of two opposite ends thereof, burner means respectively mounted in each of the said ends of the furnace at opposite sides of the hearth, the said burner means including a casing having therein a plurality of spaced parallel fuel ducts and being of approximately the same width as the hearth, means for the regulated introduction of air selectively to either casing between the said spaced fuel ducts therein, gas outlets disposed within the furnace respectively between the hearth and a corresponding burner, the said gas outlets being in regulated communication respectively with a corresponding regenerator, at least one gas-swept solid-fuel pulverizer adapted to be connected with each of the respective burners, means selectively connecting each of the regenerators with the pulverizer, and means for inducing a regulated flow of flue gases selectively from either regenerator through the pulverizer and to the corresponding burner.
50. An open-hearth furnace comprising in combination, a hearth, regenerative chambers respectively adjacent each of two opposite ends thereof, burner means respectively mounted in each of the said ends of the furnace at opposite sides of the hearth, the said burner means including a casing having therein a plurality of spaced parallel fuel ducts and being of approximately the same width as the hearth, means for the regulated introduction of air selectively to either casing between the said spaced fuel ducts therein, gas outlets disposed within the furnace respectively between the hearth and a corresponding burner, the said gas outlets being in regulated communication respectively with a corresponding regenerator, at least one gas-swept solid-fuel pulverizer adapted to be connected with each of the respective burners, means selectively connecting each of the regenerators with the pulverizer, and means for inducing a regulated flow of flue gases selectively from either regenerator through the pulverizer and to the corresponding burner.
55. An open-hearth furnace comprising in combination, a hearth, regenerative chambers respectively adjacent each of two opposite ends thereof, burner means respectively mounted in each of the said ends of the furnace at opposite sides of the hearth, the said burner means including a casing having therein a plurality of spaced parallel fuel ducts and being of approximately the same width as the hearth, means for the regulated introduction of air selectively to either casing between the said spaced fuel ducts therein, gas outlets disposed within the furnace respectively between the hearth and a corresponding burner, the said gas outlets being in regulated communication respectively with a corresponding regenerator, at least one gas-swept solid-fuel pulverizer adapted to be connected with each of the respective burners, means selectively connecting each of the regenerators with the pulverizer, and means for inducing a regulated flow of flue gases selectively from either regenerator through the pulverizer and to the corresponding burner.
60. An open-hearth furnace comprising in combination, a hearth, regenerative chambers respectively adjacent each of two opposite ends thereof, burner means respectively mounted in each of the said ends of the furnace at opposite sides of the hearth, the said burner means including a casing having therein a plurality of spaced parallel fuel ducts and being of approximately the same width as the hearth, means for the regulated introduction of air selectively to either casing between the said spaced fuel ducts therein, gas outlets disposed within the furnace respectively between the hearth and a corresponding burner, the said gas outlets being in regulated communication respectively with a corresponding regenerator, at least one gas-swept solid-fuel pulverizer adapted to be connected with each of the respective burners, means selectively connecting each of the regenerators with the pulverizer, and means for inducing a regulated flow of flue gases selectively from either regenerator through the pulverizer and to the corresponding burner.
65. An open-hearth furnace comprising in combination, a hearth, regenerative chambers respectively adjacent each of two opposite ends thereof, burner means respectively mounted in each of the said ends of the furnace at opposite sides of the hearth, the said burner means including a casing having therein a plurality of spaced parallel fuel ducts and being of approximately the same width as the hearth, means for the regulated introduction of air selectively to either casing between the said spaced fuel ducts therein, gas outlets disposed within the furnace respectively between the hearth and a corresponding burner, the said gas outlets being in regulated communication respectively with a corresponding regenerator, at least one gas-swept solid-fuel pulverizer adapted to be connected with each of the respective burners, means selectively connecting each of the regenerators with the pulverizer, and means for inducing a regulated flow of flue gases selectively from either regenerator through the pulverizer and to the corresponding burner.
70. An open-hearth furnace comprising in combination, a hearth, regenerative chambers respectively adjacent each of two opposite ends thereof, burner means respectively mounted in each of the said ends of the furnace at opposite sides of the hearth, the said burner means including a casing having therein a plurality of spaced parallel fuel ducts and being of approximately the same width as the hearth, means for the regulated introduction of air selectively to either casing between the said spaced fuel ducts therein, gas outlets disposed within the furnace respectively between the hearth and a corresponding burner, the said gas outlets being in regulated communication respectively with a corresponding regenerator, at least one gas-swept solid-fuel pulverizer adapted to be connected with each of the respective burners, means selectively connecting each of the regenerators with the pulverizer, and means for inducing a regulated flow of flue gases selectively from either regenerator through the pulverizer and to the corresponding burner.

ALBERT L. KLEES.
